UNITED STATES PATENT OFFICE.

THOMAS KELLY AND FRANK C. SARAZIN, OF WEST SUPERIOR, WISCONSIN.

ARTIFICIAL-STONE FACING FOR BUILDINGS.

SPECIFICATION forming part of Letters Patent No. 705,846, dated July 29, 1902.

Application filed May 3, 1902. Serial No. 105,726. (No specimens.)

To all whom it may concern:

Be it known that we, THOMAS KELLY and FRANK C. SARAZIN, citizens of the United States, residing at West Superior, in the county 5 of Douglas and State of Wisconsin, have invented certain new and useful Improvements in Artificial-Stone Facings for Buildings; and we do hereby declare the following to be a full, clear, and exact description of the invention, such as will enable others skilled in the art to which it appertains to make and use the same.

Our invention relates to certain new and useful improvements in artificial-stone facings for buildings, and has for its object the provision of novel means whereby the wooden buildings of the present day may be easily equipped with stone facings, such as will enhance the value of the building and present 20 a most neat and pleasing effect to the eye.

The invention is further designed to reduce the cost of converting such wooden structures into ones having stone facings, and therefore resides in the economical construction and arrangement of parts which further 25 this desideratum.

Our invention further resides in the novel details of construction and combination of parts to be fully described in the following 30 specification and then set forth in the claims.

In the accompanying drawings, illustrating our invention as applied to a wooden structure, Figure 1 is a perspective view of a building, showing the front thereof provided 35 with the usual weather-boarding and the side thereof as being equipped with our improved stone facing, the side wall being broken away and partly in section to illustrate the manner of application; and Fig. 2 is a vertical sectional view of the side wall.

We propose to apply our stone facing to buildings without removing or otherwise disturbing the usual weather-boarding, and to this end we apply, usually at about one foot 45 apart, more or less, a series of vertical strips or laths, which extend from the vertical extremities of the wall. This is illustrated in Fig. 1 of the drawings, being designated by the numeral 1, and may also be seen in Fig. 50 2, these vertical strips or laths having a series of transverse or horizontal laths or strips secured thereto, preferably by nailing. These

transverse laths or strips are usually spaced apart at distances equal to about one inch and are represented by the numerals 2. A 55 wall having been treated by the aforesaid laths in the manner specified is then ready to receive the plastic material, which preferably consists of one-half patent plaster of any of the well-known kinds, one-half cement 60 and sand, thoroughly mixed with a small proportion of wood and asbestos fiber in order to strengthen the plastic composition, it being a well-known fact that cement itself will not adhere to wood. In the application of this 65 plastic compound it is necessary and prerequisite to the perfect formation of the artificial wall that the composition should not only entirely cover the outer surfaces of the laths running in a transverse direction, but that 70 the composition should entirely inclose the laths, and the latter may thus be said to form keys, assuring the perfect adherence of the plastic compound to the walls of the building. It should also be noted that the plastic 75 compound is applied in sufficient quantity to assure the same adhering to the weather-boarding, which by experience we have found provides a most substantial and secure foot- 80 ing or base for the slabs or blocks.

The plastic compound is indicated at 3, in the drawings, and receives the slabs or blocks 4 while in a plastic state. The latter may be readily lined up by depressing the same or adding an additional quantity of plastic com- 85 pound, as the occasion may require.

In the application of the laths or slabs we direct attention to the fact that while plastic compound may be inserted between the joints formed at the meeting edges of the same, 90 still we preferably dispense with this latter entirely and place the slabs or blocks edge to edge, effecting a material saving in time as well as material, the base or footing of plastic compound serving to exclude all moisture 95 or other changes in climatic conditions, as will be obvious.

Having thus fully described our invention, what we claim as new and useful, and desire to secure by Letters Patent, is—

1. In a device of the type set forth, the combination with the wall or the like, of a series of vertical laths secured thereto and a series of horizontal laths secured to the vertical

laths, and a plastic composition applied to the said laths and completely inclosing the horizontal laths, with a series of slabs applied to the said plastic composition, while the latter is in a plastic state, substantially as described.

2. In a device of the type set forth, the combination with the wall or the like, of a series of suitably-spaced vertical laths secured to the said wall, and a series of suitably-spaced horizontal laths carried by the vertical laths, with a plastic composition applied to the said series of laths and engaging the said wall, the plastic composition entirely surrounding

the horizontal laths and receiving a series of slabs on its outer surface, the slabs being secured solely by contact with the plastic composition, and having their edges in abutting engagement, substantially as described. 15

In testimony whereof we affix our signatures in presence of two witnesses.

THOMAS KELLY.
FRANK C. SARAZIN.
